UNITED STATES PATENT OFFICE.

KARL JOHAN THORSBY, OF OAKLAND, CALIFORNIA, ASSIGNOR TO CALIFORNIA CORRUGATED CULVERT COMPANY, OF OAKLAND, CALIFORNIA, A CORPORATION OF CALIFORNIA.

NESTABLE CULVERT.

Application filed February 18, 1925. Serial No. 9,967.

My invention relates to nestable corrugated metallic culverts, and more particularly to that type in which one of the complementary arcuate sections which form the culvert is equipped with joint-forming tongues along its side edges, alternate tongues being offset, the others remaining in the arc of curvature.

Heretofore, it has been customary to make 10 said alternating offset and non-offset tongues by means of slits or cuts directed at right angles to the longitudinal axis of the section, resulting in the tongues being rectangular.

When, therefore, the sections are nested 15 into bundles, the parallel sided tongues, due to the interference of the sides of the offset tongues of one section with the sides of the non-offset tongues of the adjacent section, cause the innermost sections of the bundle 20 to compress and decrease in diameter, while the outermost sections spread and increase in diameter, thus making it not only difficult to assemble them, but also preventing them from nesting with minimum closeness. This 25 want of closeness in the nesting is serious for two reasons, namely for economical transportation and for handling. For shipping purposes, it is essential that each bundle should comprise enough sections to produce the required volume weight equivalent. 30 In the larger sizes of culverts, the number of sections in each bundle is comparatively large and, therefore of great weight.

Again, a large market for nestable culverts is in countries where the bundles are handled by coolies. It is, therefore, of importance that the bundles contain as few sections as possible in order to make their handling easy.

40 The object of my invention is to meet the above requirements as well as to reduce the objections to a minimum.

To these ends my invention consists in the novel nestable culvert-sections hereinafter 45 fully described by reference to the accompanying drawings, in which—

Fig. 1 is a perspective view of a nested bundle of my improved culvert-sections.

Fig. 2 is a fragmental side elevation of 50 two nested sections, the flaring offset tongue of the outer section being cut away to show the clearance of the corresponding tongue of the under section.

Fig. 3 is a section on the line 3—3 of 55 Fig. 2.

It will be understood that the culvert-sections here shown are half sections only of a complete culvert, the other half sections, which are merely complementary and have straight edges that is, without tongues, present no problem of close nesting and, therefore, need not be herein illustrated since the nesting problem only concerns and is due to the alternating offset and non-offset tongues of the sections here shown.

60 In the drawings, the numeral 1 indicates the arcuate culvert-sections under present consideration. The side edges of each section are provided with tongues formed by slits or cuts extending inwardly from said 65 edges. Alternate tongues indicated by 2 are offset from the general arc of the section while the remaining tongues indicated by 3 are not offset but are left in the normal arc 70 of curvature.

75 Heretofore, the slits or cuts which form these two kinds of tongues have been parallel with each other and extend at right angles to the longitudinal axis of the section. The tongues, therefore, have been rectangular 80 with straight parallel sides, and because of the interference of the sides of the offset tongues of one section with the sides of the non-offset tongues of the adjacent section, it 85 is impossible to nest the sections to a close fit without considerable distortion. In other words the offset tongues of each section catch on the non-offset tongues of the outlying or overlying section, resulting in the spreading 90 of the sections, leaving an air space between them, and this produces a larger bundle, thus requiring more sections in order to obtain the needed weight.

95 In accordance with my present improvement instead of making the tongue-defining slits or cuts parallel with each other and at right angles to the axis of the section as has been the previous custom, I make said slits or cuts, designated by 4 in planes successively oppositely inclined to the axis of the 100 section. This results in making two shapes of tongues, one shape flaring to its extremity and the other shape tapering to its extremity, and these shapes alternate as shown. Those tongues which flare outwardly, and to 105 which the term dovetailed may be applied are offset from the normal arc of the section, and they are the tongues designated by 2. The other tongues 3 are not offset but remain in the normal arc of curvature.

Now when, as shown in Figs. 1 and 3, one section is fitted over and down upon another section it will, to the extent of its thickness, have its side edges raised higher than the side edge of the underlying section, and this will present its vacancies or spaces from which its dovetailed tongues 2 have been offset, in a correspondingly higher plane than the offset tongues of the underlying section, 5 enabling said underlying offset dovetailed tongues to freely enter said vacancies without interference with the side edges of the overlying tapered tongues 3. In other words, on account of the opposite inclination 10 of the cuts 4, the radial displacement of two adjacent nested sections will provide a clearance between the edges of each offset dovetailed or flaring tongue 2 of the under section and the adjacent edges of the 15 two tapered tongues 3 of the outer section between which said offset dovetailed sections lies, as shown at 5 in Fig. 2.

I claim:

1. Arcuate culvert sections having sides 25 with terminal edges, said sides being provided

along their edges with a succession of tongues, alternate tongues having sides converging from extremity to base and the intervening tongues having sides converging from base to extremity, said first named 30 tongues being bent at their bases to offset them from the normal arc of the culvert section, and said last named tongues lying in said arc.

2. Arcuate culvert sections having sides 35 with terminal edges, said sides having slits leading from their edges in planes successively oppositely inclined to the longitudinal axis of the section, forming along the sides a succession of tongues, alternate tongues 40 having sides converging from extremity to base and the intervening tongues having sides converging from base to extremity, said first named tongues being bent at their bases to offset them from the normal arc of 45 the culvert section, and said last named tongues lying in said arc.

In testimony whereof I have signed my name to this specification.

KARL JOHAN THORSBY.
